UNITED STATES PATENT OFFICE.

ANNE E. TOMLINSON, OF PARIS, FRANCE.

DESIGN FOR A CHILD'S DRESS OR SIMILAR GARMENT.

60,590.

Specification for Design.

Patented Mar. 7, 1922.

Application filed October 7, 1921. Serial No. 506,217. Term of patent 14 years.

To all whom it may concern:

Be it known that I, ANNE E. TOMLINSON, a citizen of the United States, residing in Paris, France, have invented a new, original, and ornamental Design for a Child's Dress or Similar Garment, of which the following is a specification, reference being had to the accompanying drawing, forming part thereof.

The figure is a front view of a dress showing the essential novelty of cut-away shoulder and full integral sleeves.

I claim:

The ornamental design for a child's dress or similar garment as shown and described.

ANNE E. TOMLINSON.
